UNITED STATES PATENT OFFICE

2,105,617

DOORKNOB

Harold D. Shaw, Fitchburg, Mass., assignor to Independent Lock Company, Fitchburg, Mass., a corporation of Massachusetts

Original application November 11, 1935, Serial No. 49,129. Divided and this application November 13, 1936, Serial No. 110,686

2 Claims. (Cl. 292—347)

This application is a division of my prior application on a Doorknob filed November 11, 1935, Serial No. 49,129.

The principal objects of this invention are to provide a construction in which a fine adjustment can be made between the thimble of the knob and the spindle so that wear can be taken up to avoid the rattling of the knob and at the same time of such an extent that it can be used for applying the knob to doors of very different thicknesses; to provide means for holding the knob with respect to the spindle under any condition of adjustment without the use of the usual radial screw; to provide positive means for holding the adjustment, and to provide a simple form of cap for the knob which can be removed easily in case of necessity.

Other objects and advantages of the invention will appear hereinafter.

Reference is to be had to the accompanying drawing, in which

Fig. 1 is a sectional view of a knob constructed in accordance with this invention;

Fig. 2 is a side view with the parts separated;

Fig. 3 is a view of the main part of the knob looking in the direction of the arrow 3 in Fig. 2;

Fig. 4 is a view looking in the direction of the arrow 4 in Fig. 2; and

Fig. 5 is an end view of the thimble.

In the form shown in all the figures the usual spindle 10 is employed. Upon this spindle screws the shank 11 and this shank is adjusted back and forth on the screw-threads for adjusting it to different thicknesses of doors and taking up any slack due to inaccurate setting or to wear. The shank is provided at its outer end with a non-circular projection 12, in this case shown as hexagonal, this part projecting from a circular flat surface 13 near the end of the shank.

The knob 14 which may be made of glass, metal or other solid material, is provided with a circular recess 15 for receiving the surface 13 of the shank and with a perforation 16 of the same

shape as the projection 12 to receive that projection and provide a positive connection between the two so that the shank and knob will turn together. On the inside the knob is provided with a flat surface 17 opposite the annular recess 15.

The knob 14 has a central perforation 38 and the flat surface 17. At the other end it has a simple shouldered circular recess 40.

A cap 41 simply has an externally threaded central projection 42 screwing into a collar 43. The threaded spindle 10 screws into the other end of the collar. A washer 44 surrounds the spindle against the surface 17. A spring 45 bears against the washer 44 and cap 41 to apply pressure to the cap. The collar 43 being threaded on the spindle 10 and on the cap 41 and the cap being held by the spring 45, the turning of the annulus 14 will be transmitted to the spindle 10 through the cap 41 and collar 43. This constitutes a simple arrangement. It is less expensive to make and maintain than the form shown in the first sheet of my above identified application.

Having thus described my invention and the advantages thereof, I do not wish to be limited to the details herein disclosed, otherwise than as set forth in the claims, but what I claim is:

1. The combination with a door knob and means for adjustably securing it to a threaded spindle, said knob having an open end, of a cap located in said open end, a member in threaded connection with the cap and with the spindle to hold the cap against displacement, and yielding means for exerting an outward pressure on the cap.

2. The combination with a door knob and means adjustably securing it to a threaded spindle, said knob having an open end, of a cap located in said open end, a collar connected with the cap by screw threads, and a spindle connected with the collar by screw threads.

HAROLD D. SHAW.
